UNITED STATES PATENT OFFICE.

ARTHUR CRANSTON, OF WASHINGTON, DISTRICT OF COLUMBIA.

WINDOW-CLEANER.

1,269,395.

Specification of Letters Patent. Patented June 11, 1918.

Application filed May 17, 1915. Serial No. 28,582.

To all whom it may concern:

Be it known that I, ARTHUR CRANSTON, a citizen of the United States, now residing at Washington, District of Columbia, have 5 invented a new and useful Window-Cleaner, of which the following is a specification.

My invention relates especially to cleaners for front windows of street cars or wind shields of automobiles, or like uses. The object is to produce a very simple, compact and effective cleaning device of such dimensions that when used on a car window it will not interfere with the opening and closing 10 of the window or require special construction of the window sash or frame.

The characteristics and advantages of the invention will be further pointed out hereinafter, so far as is necessary, in connection 20 with a detailed description of the accompanying drawing, which illustrates some embodiments of the invention.

It is to be understood that the invention is capable of embodiment in other forms, and I do not limit myself to details except 25 as claimed hereinafter.

Figure 1 is a front elevation of the front end of a street car showing the invention applied thereto.

Fig. 2 is an enlarged vertical section 30 through a car window-sash and frame, showing the invention properly located on the window glass.

Fig. 3 is an enlarged section in the axis of the rotary part of the cleaner.

Fig. 4 is an enlarged fragmentary rear elevation.

Fig. 5 is a fragmentary vertical section 35 through one of the cleaner arms.

Fig. 6 is a similar view of the other arm.

Fig. 7 is a vertical section of a modification.

Fig. 8 is a front elevation of another modification.

Fig. 9 is a section of the latter.

Fig. 10 is a detail of a gasket.

Referring first to Figs. 1 to 6 inclusive, the invention is here shown applied to the front window of a car vestibule. S is the sash, G the glass therein, A the sill and P the pit or recess to receive the sash when the window is open. The invention is adapted to a window which may open vertically or horizontally, the drop type of sash being chosen as an example, and one of the objects

is to so construct and arrange the cleaner 55 that it will not increase the ordinary dimensions of the window or its frame and will not interfere with the easy opening and closing of the window.

At a suitable point in the glass, usually 60 a little below the eye level of a man of ordinary height, is cut a hole 5. In this is placed a thimble 6 to constitute a bearing, and this thimble has a flange 7. A disk 8 apertured to accommodate the thimble is 65 placed at the inside of the glass. Preferably, a gasket or washer 9 of felt, rubber or other suitable material is placed between flange 7 and the glass and between disk 8 and the glass to insure an even cushioned 70 contact of these clamping devices with the glass. These washers 9 are also preferably supplied with holes 10 which have a suction effect to insure the more complete clamping of the thimble to the glass. 75

Within the bearing formed by thimble 6 is revolvably mounted a stud 11 constituting the shaft of hub 12, which is dished to accommodate flange 7. To the hub the cleaner arm or arms 13, 14 are secured. These will 80 be more particularly described later. Extending inward from this inner end, stud 11 has a screw-threaded bore 15 and at the bottom of this bore is an angular socket 16. In a particular example this socket may be 85 of square cross-section. A nut 17 is provided to engage screw-thread 15, and this nut has passing through it an angular hole 18, the cross-sectional shape of this hole being the same as that of socket 16. The nut 90 also has a flange 19 extending outward sufficient to overlap the inner end of thimble 6. A cap nut 20 is provided, having an internal screw-thread 21 to engage an external thread formed on the inner end of thimble 6. At 95 the outer end, this cap nut has a top 21^a apertured at the center.

A square stem 22 is provided to fit the square hole in nut 17 and the square socket 16. This stem has an enlarged head 23 passing through the hole in the top 21^a of cap nut 20. A flange 24 is fixed on the stem against the inner end of head 23. An operating handle or key 25 is provided, having a clevis 26 to accommodate head 23. At 100 each side of the clevis is an eye 27 and the head is provided with a transverse hole so that pin 28 may be passed through said hole

and said eyes 27. In a preferred construction, the hub 12 is provided with two arms 13 and 14 and these may be arranged at an angle to the glass. Arm 13 may be provided with a rubbing and cleaning strip 13^a of rubber or other suitable material and the other arm may be provided with a beveled edge 14^a to directly engage the glass and cut therefrom sleet or ice. Evidently, the number of arms may be varied if desirable, also the particular construction of the arms and their rubbing or scraping devices may be varied at will.

In applying the device to the window after the hole 5 has been made therein, the flanged thimble 6 and disk 8 are first put in place, as previously described. The dished hub 12 is then put in position with stud 11 in the bearing in thimble 6. Nut 17 is then screwed into the stud. Cap nut 20, stem 22 with its flange 24 and handle 25 are usually assembled in the positions shown in the drawing in the course of manufacture. Stem 22 may now be inserted in the hole in nut 17 and the nut may be tightened as much as desired by turning the handle, the stem 22 serving as a wrench. The hole in the nut is left in line with the socket 16 and stem 22 is pushed farther in until it engages the socket. The cap 20 is then screwed up on the thread of thimble 6 until the inner end of the cap bears against disk 8 and the disk and flange 7 are drawn together to clamp the glass about the hole with sufficient tightness, preventing the bearing thimble 6 from rotating and strongly reinforcing the glass about the hole. In screwing up the cap 20, stem 22 enters farther into socket 16.

It will be noticed that the above described construction and arrangement provides for varying thicknesses of glass. With a thinner or thicker glass the cap nut 20 will be screwed a greater or less distance inward upon the thimble and stem 22 will enter more or less into the socket 16. The cleaning device may thus be adapted to any thickness that may be encountered in use without any particular attention on the part of the workman and will operate satisfactorily in any case.

When the parts are in position as described, ordinarily the arms 13, 14 are left horizontally, as in Fig. 1. The pin 28 of handle 25 is arranged parallel to the arms so that when not in use the handle hangs downward as in Figs. 2 and 4, parallel to the glass. The window may then be opened and closed without interfering with the casing, the design of the parts being such that the end of head 23, the part farthest away from the glass at the inside, will clear the casing without interference. In an extreme case, if the sash is unusually thin, 65 and the head 23 might therefore strike the

inner part of the sill, a slight notching of the sill at this point would be sufficient to prevent that difficulty.

When the window is raised, if the glass becomes obscured by rain, sleet, snow or ice, the car driver may easily raise the handle to horizontal position and rotate it, and the stem 22 engaging socket 16 will rotate hub 12 and the arms and clear a circular space C on the window to afford clear vision. When the arms are left in horizontal position and the handle is released, it will fall parallel with the glass and entirely out of the way.

The appliance may be easily and quickly removed in a manner which will be evident from the previous description.

To facilitate the application of the device to the window, in some cases it may be desirable to provide registering perforations 30 in hub 12 and disk 7. In setting up the appliance a pin may be inserted in these perforations so that the hub and flange will be temporarily locked together. The setting up of nuts 17 and 20 may thus be accomplished without the possibility of the thimble 6 and its flange revolving during these operations.

The hole 30 may also be utilized as a lubricating device by providing the outer face 95 of flange 7 with a groove 31 leading from hole 30 to the bore of thimble 6 so that the bearing may be easily oiled through the hole 30.

Fig. 7 shows a modification in which stem 22 simply engages a socket in nut 17, this socket not being extended entirely through the nut and no socket being provided in the hub 12. This arrangement is satisfactory when the handle is turned in a direction 105 corresponding to the lead of screw of nut 17; that is, if the screw is right-handed the handle may be turned right handedly without loosening the nut. Or, if separate, independent means are provided for locking the 110 nut, the handle in this case may be turned in either direction.

Fig. 9 shows another modification in which the bearing comprising thimble 6, flange 7, its co-operating disk 8 and cap nut 20 are substantially as in Fig. 3. A bolt hole 35 is in this construction bored entirely through stud 11. At the outer end of this hole is an angular countersink 36. This may be square in a representative embodiment. Bolt 37 passes through hole 35 and extends therefrom and has a head 38 to fit countersink 36. Within the countersink under the head of the bolt, may be placed one or more washers 39. Near its inner 125 end the bolt is provided with a slot 40. Upon the bolt is screwed a flanged nut 41 and this nut is provided with a transverse hole to receive a pin 42 which also passes through slot 40. The pin engages eyes 27 130

of a handle 25 similar to the one previously described.

When the device of Fig. 9 is to be applied to a relatively thick glass, some or all of the washers 39 are removed and the bolt head will then approach the bottom of the countersink and the bolt will extend out relatively far at the inside of the glass, providing for the relatively small distance the cap 20 may be screwed upon the thimble in this case. With the bolt in position, the cap 20 is first screwed up to lock the bearing on the glass and the nut 41 is then screwed upon the bolt until its flange engages the outer face of cap 20 to lock the stud 11 and its hub in revoluble position. The holes in the nut are brought in line with slot 40 in the bolt; eyes 27 of the handle are placed in line with the holes and the pin 42 inserted; the parts are thus retained positively in operative position. In case of a thinner glass, one or more washers 39 may be placed under the bolt head within the countersink, as shown in the drawing, and this not only provides for adjustment of the device to a thinner glass but prevents increasing the inner thickness of the apparatus because by this means the inner end of bolt 39 is drawn toward the surface of the glass and kept at the smallest possible distance therefrom, thus preventing interference with the window frame by any part of the cleaning appliance.

Various modifications may evidently be made without departing from the spirit of my invention.

I claim:-

1. In a device of the class described designed to be applied to a glass pane having an aperture, the combination of a bearing thimble passing through the aperture and having a flange at the outside of the glass, a disk surrounding the thimble at the inside of the glass, a screw cap engaging the thimble to clamp the flange and disk upon the glass, compressible washers between the flange and disk and the glass, a hub having a stud extending within said bearing thimble, a turning device adjustably engaging the stud, means for securing the turning device to the stud, a handle pivot-

ally secure to the turning device and one or more cleaner arms carried by said hub and bearing against the outer face of the glass.

2. In a device of the class described designed to be applied to a glass pane having an aperture, the combination of a metal bearing therein, disks at the inside and outside of the glass to secure said bearing thereto, compressible washers between the disks and the glass, a screw-piece to press the disks against the glass and hold the bearing in position, said screw-piece being stationary in relation to the bearing and disks when in position, a hub having a stud extending into said bearing and revoluble therein, a threaded member engaging an internal thread in the stud and having a flange to engage the end of said bearing and prevent end movement of the hub, registering apertures of angular cross-section in said stud and threaded member, a stem of angular cross-section engaging both of said apertures for the rotation of the hub and to lock said threaded member in relation thereto, said stem being retained in position by said screw-piece first above mentioned, and a handle pivoted to the outer end of said stem.

3. In a device of the class described designed to be applied to a glass pane having an aperture, the combination of a bearing member having a sleeve within the aperture and a flange at one side of the glass, another flange at the other side of the glass, gaskets between the said flanges and the glass, a threaded cap engaging the bearing sleeve and locking the flanges upon the glass, a hub having a stud within the bearing sleeve, said stud having an angular socket and a screw-threaded counterbore, a screw plug engaging said threaded counterbore and having a flange engaging the end of said bearing sleeve, said screw-plug having an angular hole registering with the socket in said hub, a stem of angular section passing through the hole in said screw-plug and engaging the socket in said hub, a flange on the stem held in position by the end of said screw-cap, and a foldable operating handle connected to the end of said stem.

ARTHUR CRANSTON.
